UNITED STATES PATENT OFFICE.

WILLIAM H. LOONIE, OF WAPPINGER'S FALLS, NEW YORK.

DESIGN FOR A SPOON-HOLDER.

SPECIFICATION forming part of Design No. 32,420, dated April 3, 1900.

Application filed March 6, 1900. Serial No. 7,801. Term of patent 7 years.

To all whom it may concern:

Be it known that I, WILLIAM H. LOONIE, a citizen of the United States, and a resident of Wappinger's Falls, in the county of Dutchess and State of New York, have invented and produced a new and original Design for a Spoon-Holder, of which the following is a full, clear, and exact description.

Reference is to be had to the accompanying drawings, forming a part of this specification, in which similar characters of reference indicate corresponding parts in both the views.

Figure 1 is a perspective view of a spoon-holder embodying my design, and Fig. 2 is an end view of the same.

The invention relates to holders for removable attachment to kitchen utensils and for supporting spoons or like stirring devices used in the process of cooking.

The design in its entirety consists of a bar A, having a downwardly-curved portion A'

and angular ends B, terminating in arms C, standing approximately at right angles to the angular ends B and in a direction transverse to the bar A, the ends of the arms terminating in hooks D, standing in a plane passing through the arms C and the ends B.

The leading features of the design consist of the bar, the angular ends, and the transverse arms having the hooks.

Having thus fully described my invention, I claim as new and desire to secure by Letters Patent—

The design for a spoon-holder, as herein shown and described.

In testimony whereof I have signed my name to this specification in the presence of two subscribing witnesses.

WILLIAM H. LOONIE.
